(57) **CLAIM**

We claim the ornamental design for a golf club head, as
shown and described.

DESCRIPTION

FIG. 1 is a perspective view of a golf club head, as viewed
from the bottom and one side, according to one embodiment.
FIG. 2 is a front elevation view of the golf club head of FIG.
1.

FIG. 3 is a rear elevation view of the golf club head of FIG.
1.

FIG. 4 is a side elevation view of a toe side of the golf club
head of FIG. 1.

FIG. 5 is a side elevation view of an opposite heel side of the
golf club head of FIG. 1.

FIG. 6 is a top plan view of the golf club head of FIG. 1; and,
FIG. 7 is a bottom plan view of the golf club head of FIG.
1.

The dashed lines in the drawings are for purposes of
illustrating environmental structure as well as portions of the
design that form no part of the present claimed design.
